UNITED STATES PATENT OFFICE.

FRANK E. BRIGHTMAN, OF SANDUSKY, OHIO, ASSIGNOR TO THE BRIGHTMAN HAMMERED NUT & MANUFACTURING COMPANY, OF SANDUSKY, OHIO, A CORPORATION OF OHIO.

AUTOMATIC METAL-WORKING MACHINE.

937,762.

Specification of Letters Patent.

Patented Oct. 26, 1909.

Application filed April 22, 1908. Serial No. 428,609.

To all whom it may concern:

Be it known that I, FRANK E. BRIGHTMAN, citizen of the United States, resident of Sandusky, county of Erie, and State of Ohio, have invented a new and useful Improvement in Automatic Metal-Working Machines, of which the following is a specification, the principle of the invention being explained, and the best mode in which I have 5 contemplated applying that principle, so as to distinguish it from other inventions.

This invention relates, as indicated, to automatic metal working machinery and especially to machines of this class designed 15 for cutting or forming various sorts of small articles from rods. Thus, the particular type of machine illustrated, as will be presently seen, is designed for the cutting of nut blanks from rods of the proper cross section, 20 so that in effect the operation is that simply of severing successive portions from the rod. The formation of these particular articles, however, is merely illustrative of the general operation involved in the invention.

25 Said invention has as its object the simplification of machines of this character, it being well known that the prevailing forms are among the most complex types of automatic machinery.

30 To the accomplishment of the above and related ends, said invention, then, consists of the means hereinafter fully described and particularly pointed out in the claims.

The annexed drawings and the following 35 description set forth in detail certain mechanism embodying the invention, such disclosed means constituting, however, but one of various mechanical forms in which the principle of the invention may be used.

40 In said annexed drawings: Figure 1 represents in front elevation, the lower portion of the supporting frame being omitted, a series of metal working machines embodying my invention and specifically designed for the 45 purpose referred to above; Fig. 2 is an end view of the same; Fig. 3 is a horizontal sectional view of a detail of one such machine taken on the line 3-3, Fig. 2; Fig. 4 is a corresponding vertical section and side elevation of the same detail; and Fig. 5 represents the general mode of operation illustrated in such machine; Fig. 6 is a sectional

view of the chuck and its actuating mechanism.

The complete machine illustrated in Fig. 55 1 consists, as has been indicated, of an assemblage of substantially duplicate devices B, each embodying in its construction the several elements of the invention. The description of a single one of these component 60 machines or devices will hence suffice, first noting that all are mounted in a common frame A comprising end members a a and suitable transverse supporting members a'. a'. Longitudinally alined in such frame is 65 a cam shaft C standing in similar operative relation to each of the component machines while vertically alined in the frame is a series of shafts c, one for each individual device. Each of the component devices, or 70 machines, B, that enter into the structure illustrated in Fig. 1 comprises as a prime element a hollow spindle b of familiar construction vertically supported in suitable bearings a² in the horizontal members a' of 75 the frame. Such spindles are driven, by means of belts c or other connections, from a main drive shaft C' disposed horizontally with and to the rear of the machine frame. Each spindle is furthermore provided with 80 a cone or stepped pulley b' by means of which the motion thus received from main drive shaft C' is communicated to the intermediate vertical drive shafts C² through belts c², and thence in turn to cam shaft C 85 through a worm c³ and worm gear c⁴. A second shaft C³ alined with, and lying below, cam shaft C, bears a plurality of worm gears c⁵ rotatably mounted thereon and driven by worms c⁶ on vertical shafts C². 90 Such gears c⁵ are effective to control a stop device and the cutting tools, as will be later described. Each hollow spindle b is designed to receive a separate piece of stock in the form of rods or bars D and being vertically arranged, it will be obvious that the stock will be fed downward therethrough by gravity as occasion is offered. To hold the stock and cause the same to rotate with the spindles, suitable gripping mechanism of the 95 form illustrated in Fig. 6 is employed. Such parts consist of the cone sleeve b⁸ adapted to actuate bent lever b⁴ that are connected in turn to reciprocate an inner tube b¹⁰ and

thereby open and close the chuck b^1 at the lower end of the spindle. Movement of the cone sleeve b^3 is controlled by means of a lever c^7 that is oscillated by a heart cam c^8 formed in the lateral face of the corresponding worm-gear c^4 on cam-shaft C. The stock being free to move downwardly under the influence of gravity except when the gripping means just described are closed, it is merely necessary to interpose below it a suitable stop shown in the form of a plate b^9 , Figs. 3 and 5, by means of which a portion of the rod of a predetermined length is allowed to project below the end of the spindle b . This downward feeding movement will obviously follow instantly upon release of the gripping device.

For the simple cutting-off operation, that alone is necessary in the formation of articles of the character in hand, tool bearing members in the form of two arms B' pivotally mounted about an axis adjacent to the lower ends of stock-holding spindle are provided, Figs. 3 and 4. Such arms are arranged so that their forward ends may be moved across the lower end of the spindle and the tools b^5 b^6 , borne thereby, be thus brought into operative relation to successive portions of the stock D as such portions are presented thereto by the several means aforesaid. In form the tools b^5 b^6 will of course vary with the character of the operation to be performed; as illustrated in Figs. 3, 4, and 5, they comprise arc-shaped blades adjustably secured on the outer ends of the arms so as to have their cutting edges directed inwardly or toward each other; the one such cutter b^6 will be preferably a roughing tool, while the other gives the final form to the object produced. Normally the outer ends of the arms, together with the cutters borne thereby, are held in retracted position by means of a tension spring b^7 connecting the rear ends of the two arms B'. The latter are forced apart and such cutters closed upon the work by means of a disk bearing lateral cams c^8 adapted to simultaneously force apart the rear arm ends. As shown in Fig. 4, the cutters appear in their closed or final cutting position. Rollers b^8 are mounted upon such ends in order to reduce the friction, and the worm gear c^5 , previously referred to, constitutes the cam disk.

Having thus described with sufficient detail the structure of my improved machine, its mode of operation will, it is thought, be so obvious as to require very little further explanation. The stock, which may be of any suitable length, will for the formation of articles such as nut blanks be ordinarily formed of the cross section desired in the finished article. It will hence only remain to sever these in succession from the end of the rod giving by means of the severing tool

such modification of form as it is desired the article should have. The stock thus placed in a spindle, assuming the cutting tools be withdrawn, will drop until it contacts with the stop. Immediately thereafter the gripping means are actuated from the cam shaft C to grip such stock in the spindle. The latter being now firmly held in the rotating spindle the stop may if desired be withdrawn, and thereupon the cutting tools advanced in the manner already described. Such advance continues until the projecting portion of the stock has been severed; immediately such severed portion drops from the machine, the tools are quickly and simultaneously retracted, the stop advanced, and the gripping means caused to release the stock in the spindle. Thereupon a further section of stock is presented, and the former operations may then be repeated.

While stop plate b^9 , for gaging the successive lengths of stock fed down by the stock-holding spindles, may be supported and actuated in any suitable fashion, a very simple and convenient arrangement is to secure such plate to the inner face of one of the arms B', its position being such that when the arms are open and tools b^5 b^6 retracted, the plate will be interposed in the path of rod D. When the arms close, which of course is timed to occur after the stock has again been gripped in the spindle, plate b^9 is withdrawn into the inoperative position shown in Fig. 4.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention.

1. In mechanism of the class described, the combination of a stock-holding spindle disposed so that the stock may be fed therethrough by gravity, means movable into and out of line with said spindle for gaging the length of stock thus fed, means for intermittently operating said gaging means, means for gripping the stock in said spindle, means for rotating said spindle, and means for operating upon successive portions of the stock as they are presented thereto by the several means aforesaid.

2. In mechanism of the class described, the combination of a stock-holding spindle disposed substantially vertically, whereby the stock may be fed therethrough by gravity; a transversely disposed drive shaft connected to rotate said spindle; vertically reciprocable chuck opening and closing means on said spindle; a cam rotatable about an axis parallel with said drive shaft and con-

nected to actuate said last named means; means coöperative with said spindle for gaging the length of stock fed downwardly therethrough when the chucks are open; 5 means for operating upon successive portions of the stock as they are presented thereto; a vertically disposed shaft in connection with said spindle and connected to be driven therefrom; and gearing connecting the ends of said vertically disposed shaft with the 10 corresponding rotatable cam and operating means.

Signed by me this 18th day of April 1908.

FRANK E. BRIGHTMAN.
